(57) CLAIM

The ornamental design for a promotional device, as shown and described.

DESCRIPTION

FIG. 1 is a rear view of a promotional device showing our new design in an unfolded configuration without a content insert;

FIG. 2 is a front view of the promotional device showing the design in an unfolded configuration with a content insert in a retracted state, a center flap in an extended state, and a foldout sheet in a retracted state;

FIG. 3 is a front perspective view of the promotional device showing the design in a partially folded configuration with the content insert in a retracted state, the center flap in a retracted state, and the foldout sheet in a partially retracted state;

FIG. 4 is a front perspective view of the promotional device showing the design in an unfolded configuration with the content insert in a retracted state, the center flap in an extended state, and the foldout sheet in a partially retracted state;

FIG. 5 is a front perspective view of the promotional device showing the design in a partially perforated state with the content insert in a retracted state, the center flap in an extended state, and the foldout sheet in a partially retracted state;

FIG. 6 is a front view of the promotional device showing the design in an unfolded configuration with content insert in a retracted state, the center flap in an extended state, and the foldout sheet in a partially extended state; and,

FIG. 7 is a front view of the promotional device showing the design in an unfolded configuration with content insert in a retracted state, the center flap in an extended state, and the foldout sheet in an extended state.

The foldout sheet extending from the body of the design in FIGS. 6 and 7 retracts into the body of the design as shown in FIGS. 2-5. The broken lines in FIGS. 1, 2, and 4-7 represent perforation lines. Any unshown portion of the promotional device forms no part of the claimed design.
